UNITED STATES PATENT OFFICE.

JAMES WOOD STOCK, OF NOTTINGHAM, ENGLAND.

DRAFT APPARATUS FOR FURNACES OF STEAM-BOILERS OR THE LIKE.

SPECIFICATION forming part of Letters Patent No. 691,672, dated January 21, 1902.

Application filed June 14, 1901. Serial No. 64,574. (No model.)

To all whom it may concern:

Be it known that I, JAMES WOOD STOCK, a subject of the King of Great Britain and Ireland, residing at Nottingham, in the county 5 of Nottingham, England, have invented new and useful Improvements in Draft Apparatus for Furnaces of Steam-Boilers or the Like, of which the following is a specification.

This invention relates to apparatus or arrangements of air-pipes to be applied to steam-boilers of all kinds—stationary, locomotive, and marine; and it has for its object to insure perfect combustion of the fuel, absence of smoke, and utilization of the waste heat 15 radiated from the boiler and in the uptake.

For the purpose of my invention I provide in a suitable position relatively to the furnace-chimney or between the furnace-chimney shaft and the furnace or back of the 20 boiler or in the chimney-stack a number of tubes disposed in one or more rows, said tubes being open to the atmosphere at one end and connected at the other to a pipe (or pipes) which passes at the side of the boiler and in 25 front of the furnace, where it (or they) opens (or open) into the furnace through the coaling-doors. By this arrangement air is drawn into the tubes near the chimney and at the hottest or a very hot part of the flue, and after 30 absorbing the heat which would otherwise be wasted is caused to pass through piping above the level of the furnace-bars or furnaces and close to the boiler, and thus absorb the heat radiated from the boiler. It is thence 35 conducted to the front of the furnace and delivered above the fire-bars upon the fuel, either as a forced or natural draft, at a temperature of 400° to 900° Fahrenheit. The arrangement and construction of the piping and 40 parts and the dimensions thereof, as well as the number of air-inlets, must obviously be varied according to the design of the boiler and furnace; but in general construction the arrangement is as shown in the annexed 45 drawings, in which—

Figure 1 is a cross-section at the back of the boiler. Fig. 2 is a plan, and Fig. 3 is a front elevation, of a boiler of the Cornish or Lancashire type with my invention applied 50 thereto. Fig. 4 is a detail in elevation of the

connection between the sections of the air passage or pipe, and Fig. 5 is a sectional plan view of the same.

a represents the air inlet pipes, which may be vertical, as shown, or may be horizontal or inclined. They are arranged in the flue near the uptake, so that the gaseous products of combustion pass between and around them, and said pipes may be cast or composed of steam-pipe or of any kind of metal. Their 55 openings *b* for the inlet of air may be provided with a fan near the furnace-chimney. The air is received from all said pipes *a* into pipes *c*, and from these the air is drawn either by the draft of the fire or otherwise 60 along the pipes *d* over the top of or at the back of the boiler and from these in two or more streams through pipes *e*, by which it is conducted to the front of the boiler or furnace, as seen in Fig. 3. The air, which has 65 been highly heated in its passage through the above-mentioned piping, is now delivered through the open ends *g* upon the burning fuel in the furnace, and thus facilitates the combustion of the fuel and increases the 70 draft and velocity with which air is drawn in at the openings *b* at the same time.

Various changes within the scope of the appended claims may be made.

The back draft on opening the coaling-doors is avoided by the construction of the joint in the piping at the door or doors of the furnace. The pipe is divided at an angle, as seen at *h* in the plan view, Fig. 2, and in the detail views, Figs. 4 and 5, so that when the 80 coaling-door is closed the two sections of the air-pipe are in alinement; but on opening the coaling-door the mouthpiece *g* separates from the remainder of the pipe *f*, thus causing communication between the interior of the furnace and the pipe *f* to be cut off at the joint, the inclination of which allows this result to be attained by a simple butt connection of the 85 pipes.

Having now described my invention, what 90 I claim, and desire to secure by Letters Patent, is—

1. A steam-boiler and its furnace combined with a pipe for supplying air to said furnace and including two abutting sections, the 100

abutting faces being beveled and one of said sections being connected with the door of said furnace.

2. A steam-boiler and its furnace combined
5 with a pipe for supplying atmospheric air to
said furnace, the pipe being arranged to be
heated by the gaseous products of combus-
tion during their passage to the chimney, and
including two separable sections having abut-
ting beveled faces one of which is located in

the flue, near to the uptake and leads to the
front of the furnace, and the other of which
is connected with the door of said furnace.

In witness whereof I have hereunto signed
my name in the presence of two subscribing ¹⁵
witnesses.

JAMES WOOD STOCK.
